UNITED STATES PATENT OFFICE.

JACOB BININGER, OF NEW YORK, N. Y.

CIGARETTE-MACHINE.

SPECIFICATION forming part of Letters Patent No. 240,367, dated April 19, 1881.

Application filed February 2, 1881. (Model.)

To all whom it may concern:

Be it known that I, JACOB BININGER, a citizen of the United States, residing in the city, county, and State of New York, have invented 5 a certain new and useful Improvement in Machines for Making Cigarettes, of which the following is a specification.

My invention relates to machines for making cigarettes. Its object is to provide a simple and easy method of making cigarettes by means of a device that can be constructed at a low price, easily carried in the pocket, and afford persons whose fingers are naturally unskillful or stiffened by cold a way of making 15 their own cigarettes readily and accurately. I attain these objects by the mechanism illustrated in the accompanying drawings, in which—

Figure 1 represents a cylindrical tube, A, 20 with an interior space of the size and shape desired for the cigarette, closed at one end by the stopper a, and open at the other end. The stopper a projects into the tube A in a hemispherical, conical, or tapering shape to form 25 a guide for the twister, and at its exterior end it forms the handle L. The top of the tube is open on one side throughout its length, except where closed by the stopper a, and above the space in which the cigarette is formed it has 30 a lid arranged to work on a hinge, b b, so as to open for the admission of the twister and of the tobacco. The edge of the tube opposite the hinge is bent slightly outward, so as to form a lip, F. The hinge of the lid B is so 35 made as to have an aperture, D, for the cigarette-paper to pass freely underneath it into the tube.

Fig. 2 represents the twister, to be inserted in the space or chamber in which the cigarette 40 is to be formed, and made to fit it, but allowing sufficient room for the paper to be wound around it. It consists of a cylinder made of a size to correspond with the interior of the tube A, a portion, preferably about one-half of said 45 cylinder, being cut away in the line of the axis of the cylinder, as shown in the portion H, so that said twister is in the form of a concave gutter throughout the length of the chamber in which the cigarette is to be formed. One end of this 50 tube is open and is guided by the tapering

stopper a. The other is closed by a stopper, c, which may be extended to form a handle, K, opposite to the handle L.

Fig. 3 represents the entire machine, the twister C in the tube A, and the cigarette-paper J partly through the space or aperture D, between the hinge and the tube and around the twister.

Fig. 4 represents a method of attaching the twister C to the tube A by means of the collar 60 N, hinged upon the end of the tube opposite to the stopper a, and on the side opposite to the lid B. This collar passes around the neck of the twister C, between the handle K and ridge d, and the twister should have sufficient play 65 in the collar to allow its open end to pass the projection a when lifted from the tube.

The best method of using my invention is as follows: Place the twister (represented in Fig. 2) in the tube, (represented in Fig. 1,) the lid 70 being open. Fill the gutter with tobacco, packing it into the gutter by pressing down the lid. Then turn the twister one-quarter around to free the space under the hinge from any loose tobacco. Open the lid and insert an 75 ordinary cigarette-paper through the opening under the hinge. Close the lid and turn the twister till all but a small part of the paper has been drawn into the tube, which part may then be moistened so as to adhere, in order to close 80 the cigarette, or gum may be previously put on the edge of the paper, so that it will adhere better when moistened. Then turn the twister till all the paper has passed into the tube. It is now wrapped around the twister, inclosing it and the 85 tobacco. Then, by the handle, withdraw the twister, with the cigarette rolled upon it, or when the contrivance shown in Fig. 4 is used 90 the lid may be opened and the twister pulled out, so as to escape the end of the stopper a, and raised on the hinge f, and the cigarette is then drawn off it.

It is not necessary that the paper should pass through the opening under the hinge. The same result may be obtained by placing 95 the paper first in the tube, then placing the twister in the tube upon the paper, then filling the twister with the tobacco, closing the lid, and proceeding as before, moistening the edge of the paper on the lip.

Having fully described my invention, what I desire to claim and secure by Letters Patent is—

1. A machine for making cigarettes, consisting of the tube A, with lid B, combined with a concave twister, C, within the tube, and extending the length of the tube or chamber within which the cigarette is formed, substantially as described.
- 10 2. In a machine for making cigarettes, the tapering stopper *a*, forming one end of, and projecting into, the chamber in which the cigarette is formed, as a guide for the twister, in combination with the tube A and the twister C, substantially as described.
- 15

3. In a machine for making cigarettes, the combination of the cylindrical chamber A, provided with the aperture D, with hinged lid B, substantially as described.

4. In a machine for making cigarettes, the combination of the twister C, attached to one end of the tube A, with the collar N and hinge *f*, substantially as described.

JACOB BININGER.
